US0D1071339S

(12) **United States Design Patent** (10) Patent No.: **US D1,071,339 S**
(45) Date of Patent: ** Apr. 15, 2025

(54) **BASE LAYER GARMENT**

(71) Applicants: **Barry Robertson**, Didcot (GB); **Stuart Robertson**, Didcot (GB)

(72) Inventor: **Barry Robertson**, Didcot (GB)

(**) Term: **15 Years**

(21) Appl. No.: **35/519,536**

(22) Filed: **Sep. 11, 2023**

(80) **Hague Agreement Data**

Int. Filing Date: **Sep. 11, 2023**

Int. Reg. No.: **DM/233947**

Int. Reg. Date: **Sep. 11, 2023**

Int. Reg. Pub. Date: **Dec. 29, 2023**

(30) **Foreign Application Priority Data**

Mar. 14, 2023 (GB) 6268264

(51) **LOC (15) Cl.** **02-02**

(52) **U.S. Cl.**

(57) **CLAIM**

The ornamental design for a base layer garment as shown and described.

DESCRIPTION

1. Base layer garment

1.1 : Front Perspective View

1.2 : Left

1.3 : Back Perspective View

1.4 : Right

A base layer garment for use in hazardous environments; the thin lines in the reproduction represent creases only and do not illustrate ornamentation or decoration on the surface of the product.

1 Claim, 4 Drawing Sheets
